UNITED STATES PATENT OFFICE.

BENJAMIN H. JONES, OF ST. LOUIS, MISSOURI, ASSIGNOR TO SMITH & DAVIS MANUFACTURING CO., OF ST. LOUIS, MISSOURI, A CORPORATION OF MISSOURI.

SPRING-MATTRESS AND SUPPORT THEREFOR.

1,385,174.

Specification of Letters Patent. Patented July 19, 1921.

Application filed February 4, 1921. Serial No. 442,427.

To all whom it may concern:

Be it known that I, BENJAMIN H. JONES, a citizen of the United States, residing at St. Louis, and State of Missouri, have invented certain new and useful Improvements in Spring-Mattresses and Supports Therefor, of which the following is a full, clear, and exact description, reference being had to the accompanying drawings, forming 10 a part hereof.

My invention has relation to improvements in spring mattresses for beds and supports therefor, and consists in the novel features of construction more fully set forth in the 15 specification and pointed out in the claims.

The object of the present invention is to provide a spring mattress having a frame, the component parts of which shall be spot-welded together, thus resulting in a strong, 20 durable construction possessing the rigidity of a single piece. The advantage of thus constructing the frame lies principally in its rigidity, and further in that it may be handled as a single unit while building up 25 the mattress. A further object is the provision of a marginal supporting member having brackets to which the marginal springs are secured, and also having an adjustable supporting arm or slide whereby the mattress 30 may be supported on the side-rails of the bed. A further object is the provision of a supporting slide for the mattress that is adapted to coöperate with either a regular or inverted side-rail or a wooden bed side- 35 rail, the slide being provided with prongs that will bite into and grip the wooden side-rail. Further and other advantages will be better apparent from a detailed description of the invention in connection with the accompanying drawings in which—

Figure 1 is a plan view of a part of my improved mattress and supporting slide therefor; Fig. 2 is a side elevation of one end of the mattress with the slide in place; 45 Fig. 3 is a vertical transverse section on the line 3—3 of Fig. 1 with parts omitted; Fig. 4 is an enlarged vertical cross sectional detail on the line 4—4 of Fig. 1 showing the frame members spot-welded; Fig. 5 is a perspective view showing how the springs are seated over the bosses formed on the frame; 50 Fig. 6 is a perspective view of the supporting slide coöperating with a regular rail; Fig. 7 is an enlarged cross sectional detail 55 through the slide taken on the line 7—7 of

Fig. 1; Fig. 8 is a perspective view of the slide coöperating with an inverted side-rail; Fig. 9 is a perspective view of the slide coöperating with a wooden side-rail; and Fig. 10 is an outline of the mattress showing the 60 marginal supports and supporting slides mounted thereon.

Referring to the drawings F represents the main frame of the mattress composed of a series of longitudinal metallic bands 1 and a series of transverse metallic bands 2, the bands 1 having bosses 3 bent from them between their points of intersection with the bands 2, and bosses 3' bent from the bands 1 and 2 at their points of intersection. The 65 bands 1 and 2 are spot-welded together as shown at w (Fig. 4) the weld in this instance being at the boss formation 3', but, of course, for a different spacing of the bosses this may not be the case, the object 70 being to weld the bands 1 and 2 at their points of intersection irrespective of the location of the bosses. Heretofore in mattresses of this type the bands composing the frame have been riveted together, thus permitting of a distortion of the frame when 75 certain stresses are imposed, the rivet acting as a pivotal point for the movement; but I have overcome this disadvantage by spot-welding the points of intersection of these 80 bands, the resulting frame being virtually 85 integrally formed.

The frame further comprises a marginal supporting member 4 on each side of the mattress, the supporting member in the 90 present instance being an angle iron, to the top leg of which a series of smaller angles 5 are secured in spaced apart relation, the angles 5 constituting holding members for the marginal springs 6, the lower ends of 95 said springs being passed through openings o in the angles 5. A sub-frame F' comprising outer members 7 and transverse members 8 is suspended from the marginal member 4 by struts a, the frame F' being provided 100 only when a double deck mattress is desired, in which case the lower ends of the intermediate springs 6' (which are double deck springs) are passed through the openings o' in the members 8, the springs being seated 105 on the bosses 3, 3' intermediate their extremities, the members 1 and 2 entering between adjacent coils of the springs as shown in Fig. 5. The upper coils of the springs 6, 6' are woven together by means of wires 110

9 and a marginal wire 10 extends around the entire mattress, the end springs 6' being secured to the wire 10 by clips 11, and the marginal springs 6 are bound to the wire 10 by connecting wires 12. The method of weaving or otherwise arranging wires 9 and 10 together with the springs to form the supporting surface of the mattress is old and is not claimed herein. However, a mattress 10 of this type embodying a main frame, the component parts of which are welded together to form an integral unit, is new so far as I am aware.

In order to support the mattress on the 15 side-rails of the bed I have provided a pair of adjustable arms or slides 13 slidably mounted on the supporting members 4 beneath straps 14 riveted to the members 4. The slide 13 has a depending lug 15 bent 20 from its inner edge, and a pair of fingers or prongs 16 bent downwardly from its outer edge; the lug 15 and fingers 16 operating to confine the slide on the member 4. When the mattress is positioned in a bed 25 provided with a regular side-rail 17 (Fig. 6) the slide is extended so that the fingers 16 will project over the outer edge of the rail 17, the lug 15 operating to prevent withdrawal of the slide from the strap 14. If 30 the bed is provided with an inverted side-rail 17' the fingers 16 will rest on the horizontal leg of the side-rail as shown in Fig. 8. When it is desired to place my improved mattress embodying the slide 13 on a bed 35 provided with a wooden side-rail 17" the fingers or prongs 16 of the slide will engage the rail 17" as shown in Fig. 9, and when weight is imposed on the mattress the prongs 16 will bite into the wood rail and effectively prevent displacement. The slide 13 40 has its lateral edges *e*, *e* bent downwardly, resulting in a channel formation which greatly increases the strength of the slide, and permits of using lighter material in

making the same, and the lug 15 and prongs 45 16 will, of course, project downwardly below the plane of the edges *e*.

It will be readily understood from the foregoing that I have provided a mattress that possesses lightness and durability together with great rigidity, embodying means whereby it may be supported on practically any manner of side-rail forming a part of a bed. Furthermore the slide itself may be susceptible to other uses not in connection 55 with a bed, all of which I wish to avail myself of together with the modifications to which the invention is susceptible.

Having described my invention, I claim:

1. In a device of the character described, 60 a member provided with a strap, a channel-shaped slide mounted between the member and strap, and means for holding said slide in place.

2. In a device of the character described, 65 a supporting member having a strap secured thereto, an adjustable arm mounted between the supporting member and the strap, said arm being channel-shaped and having a downwardly projecting lug on its 70 inner end, a pair of prongs bent downwardly from the outer end of the arm, said prongs and lug operating to maintain the arm on the supporting member.

3. In combination with the side rails of 75 a bed, a spring mattress having marginal supporting members, slides mounted thereon, each of said slides having a lug bent downwardly from its inner edge and a pair of prongs bent downwardly from its outer 80 edge, the lug and prongs operating to maintain the slide in engagement with the supporting member, and the prongs operating to engage the bed side-rail to hold the mattress in place. 85

In testimony whereof I affix my signature.

BENJAMIN H. JONES.
